UNITED STATES PATENT OFFICE.

HENRY KOCH, OF JAMAICA, AND FRIEDRICH H. N. WOHLERS, OF HEMPSTEAD, NEW YORK, ASSIGNORS TO DICTOGRAPH PRODUCTS CORPORATION, A CORPORATION OF VIRGINIA.

TELEPHONE RECEIVER.

Application filed November 14, 1923. Serial No. 674,601.

This invention relates to telephone receivers, particularly of the type commonly employed in radio telephone and telegraph receiving sets and popularly known as loud speakers. The invention is in the nature of improvements upon the receivers disclosed in the co-pending applications of Henry Koch, Serial No. 628,709 filed March 30, 1923, and No. 661,596 filed September 8, 1923, and has for an object to improve and simplify the mechanism for varying the influence of the electromagnetic device upon the diaphragm, and to provide an improved receiver which is exceptionally simple, durable, relatively inexpensive, and which will enable a very fine relative adjustment of the air gap between the diaphragm and pole pieces of the electromagnetic device. Other objects and advantages will be apparent from the following description of an embodiment of the invention, and the novel features will be pointed out hereinafter in claims.

In the accompanying drawing;

Fig. 1 is a sectional elevation through a receiver constructed in accordance with the invention; and,

Fig. 2 is a bottom plan of the same.

In the illustrated embodiment of the invention, a cup shaped base 1, in the nature of a shell, serves as the base of the receiver for supporting the operating parts thereof. The shell 1 is supported in an inverted position, as illustrated in Figure 1, upon any suitable surface, and is provided upon its upper face with a tubular projection 2, communicating with the interior of the base shell 1 and serving as a support for the small end of a suitable amplifier horn 3. The inner face of the shell is provided with an annular wall 4, substantially concentric with the passage of the tubular extension 2, and a suitable diaphragm 5 is fitted against this annular wall. A cup shaped frame 6 is provided along its open edge with a lateral annular flange 7 fitting against the peripheral portion of the diaphragm. Suitable fastening means, such as screws 8, pass through the flange 7 and diaphragm into the annular wall 4 for securing the cup shaped frame 6 to the base shell 1, and for clamping the periphery of the diaphragm against the annular wall.

A cup shaped member 9 is mounted in the frame 6 for sliding movement toward and from the diaphragm, and suitably supports

electromagnets 10 having pole pieces 10^a projecting from the ends thereof toward the diaphragm, so that when the member 9 moves toward or from the diaphragm, the pole pieces 10^a will move toward or from the diaphragm. The pole pieces form polar extensions of a permanent magnet within the member 9, as will be understood in the art.

A stud 11 extends from the member 9 through the frame 6, and is provided with an axial slot 12 for receiving the intermediate portion of a lever 13. A pivot member 14 passes through the stud and lever for providing an articulated connection between them. One end 15 of the lever bears upon and fulcrums upon the frame 6, so that when the other end 16 of the lever is moved in one direction, the lever, by reason of this fulcrum on the frame 6, will pull the member 9 carrying the electromagnetic device away from the diaphragm. A leaf spring 17 is interposed between the member 9 and frame 6, so as to yieldingly urge the member 9 in a direction toward the diaphragm, the spring being compressed when the lever 13 is operated to pull the member 9 away from the diaphragm. A pin 18, carried by the member 9, passes loosely through an aperture in the frame 6 so as to slide freely therein as the member 9 moves toward and from the diaphragm, and to prevent rotation of the member 9 within the frame 6. The circuit wires 20 serve to conduct a variable electric current to the electromagnets 10.

An operating member 21 extends vertically through the upper wall of the base shell, with a shoulder 22 bearing against the under face of the upper wall so as to prevent upward movement of the member 21 through the base shell. A suitable operating button 23 is forced upon, or otherwise suitably secured to, the upper projecting end of the member 21, with an indicating dial 24 between the button and member and secured for rotation with the member. The engagement of the dial 24 with the upper face of the upper wall of the base shell 1 serves to limit downward movement of the member 21 without preventing rotation of the latter. A Z-shaped bracket 25 is secured by screws 26, or other suitable means, to the upper wall of the base shell, and an end angular portion 27 thereof is provided with an aperture 27^a in which the lower end of the member 21 is rotatably mounted.

The lower end of the member 21 is provided with an axially extended, threaded recess 28, and an element 29 is received within the recess, in threaded engagement with 5 said member. The periphery of the element 29 is provided with a plurality of spaced notches 31, and a pawl or detent 32, in the nature of a leaf spring, is secured to the bracket 25 in a position to snap into any of 10 the notches 31 which may be brought into alignment therewith. The pawl or detent serves to hold the element 29 against rotation with the member 21, and therefore when the latter is rotated, the element 29 will be 15 moved axially of the member 21. The detent or pawl 32 is disposed parallel with the member 21, so as to remain within a notch 31 during the axial movement of the element 29 without releasing the latter. The 20 element 29 abuts against the end 16 of the lever 13, so that when the button 23 is rotated in one direction the element 29 will be moved downwardly to rock the lever about its fulcrum and shift the member 9 against 25 the action of the spring 17. A pin 33 depends from the lower face of the dial 24 so as to rotate therewith, and a stop pin 34 is provided upon the upper face of the base shell 1 within the path of the pin 33, the pins 30 33 and 34 serving to limit the rotation of the button 23 to approximately one revolution.

In the operation of the receiver, the circuit wires 20 are connected to any source of 35 variable electric currents such as a telephone or radio telephone or telegraph circuit. The variable currents will pass through the electromagnets 10, and vary the magnetic flux passing through the diaphragm between the 40 pole pieces 11 of the permanent magnet in accordance with the variations of the current. These variations of flux will cause corresponding vibrations of the diaphragm. The vibrating diaphragm sets up sound 45 waves which pass through the tubular extension 2 into the amplifier horn 3, where the waves are amplified and discharged. By rotating the button 23 in one direction the element 29 will be moved axially thereof and 50 rock the lever 13 about its fulcrum upon its frame 6. The lever in rocking upon its fulcrum will draw the electromagnetic device away from the diaphragm against the action of the spring 17. This serves to lessen 55 the influence of the electromagnetic device upon the diaphragm by increasing the air gap between the diaphragm and the pole pieces of the electromagnets.

By rotating the button 23 in the other 60 direction the element 29 will be moved in a reverse direction and away from the end of the lever 16, whereupon the spring 17 will operate the electromagnetic device toward the diaphragm so as to reduce the air gap between the pole pieces and the diaphragm.

This movement of the electromagnetic device carries the lever toward the element 29 and maintains the end 16 of the lever always in contact with the element 29. It will thus be observed that by rotating the button 23 70 the air gap between the pole pieces of the electromagnetic device and the diaphragm may be varied.

In order to initially adjust the air gap, the button 23 is rotated until the pin 33 of 75 the dial engages with the pin 34 on the base shell. The spring detent 32 is flexed out of engagement with the element 29, and the latter is then rotated to cause it to move along the member 21 until the electromagnetic device exerts its maximum magnetic influence upon the diaphragm without the diaphragm, during its vibrations, hitting the pole pieces 80 11. The detent 32 is then released and allowed to snap into one of the notches 21 of 85 the element 29 so as to hold the latter in this adjusted position. The rotation of the button 23 then serves to carry the electromagnetic device away from the diaphragm to an extent determined by one rotation of the operating button. The operating button being accessible from the upper face of the base may be readily and conveniently manipulated to vary the air gap and thus control 90 the sounds which are emitted by the receiver. 95

It will be obvious that various changes in the details and arrangements of parts, herein described and illustrated for the purpose of explaining the nature of the invention, may be made by those skilled in the art within the principle and scope of the invention as expressed in the appended claims. 100

Claims:

1. In a telephone receiver, a frame, a diaphragm carried by said frame, an electromagnetic unit mounted in said frame for movement toward and from the diaphragm and adapted to actuate the said diaphragm magnetically, a stud carried by the unit, a lever articulately connected at an intermediate point to said stud and having a fulcrum at one end on said frame and actuating means adapted to act on the other end of the lever to rock the lever and thereby adjust the unit relatively to the diaphragm. 110 105 115

2. In a telephone receiver, a frame, a diaphragm carried by said frame, an electromagnetic unit mounted in said frame for movement toward and from the diaphragm and adapted to actuate the said diaphragm magnetically, a stud carried by the unit, a spring device constantly urging the unit in one direction relatively to the diaphragm, and a lever articulately connected at an intermediate point to said stud and having a fulcrum at one end on the frame enabling operation of the unit in an opposite direction relatively to the diaphragm, and actuating means adapted to act on the other end of the lever to effect such operation. 120 125 130

3. In a telephone receiver, a frame, a diaphragm carried by said frame, an electromagnetic unit mounted in said frame for movement toward and from the diaphragm and adapted to actuate the said diaphragm magnetically, a stud carried by the unit, a spring device constantly urging the unit in one direction relatively to the diaphragm, a lever articulately connected at an intermediate point to said stud and having a fulcrum at one end on the frame enabling operation of the unit in an opposite direction relatively to the diaphragm, and a mechanical slow-motion device operatively associated with the other end of said lever for operating the lever against the action of the spring device.
4. In a telephone receiver, a frame, a diaphragm carried by said frame, an electromagnetic unit mounted in said frame for movement toward and from the diaphragm and adapted to actuate the said diaphragm magnetically, a stud carried by the unit, a spring device constantly urging the unit in one direction relatively to the diaphragm, a lever articulately connected at an intermediate point to said stud and having a fulcrum at one end on the frame enabling operation of the unit in an opposite direction relatively to the diaphragm, and a screw device operatively associated with the other end of said lever for operating the lever against the action of the spring device.
5. In a telephone receiver, a frame, a diaphragm carried by said frame, an electromagnetic unit mounted in said frame for movement toward and from the diaphragm and adapted to actuate the said diaphragm magnetically, a stud carried by the unit, a spring device constantly urging the unit in one direction relatively to the diaphragm, a lever articulately connected to said stud and having a fulcrum on the frame enabling operation of the unit in an opposite direction relatively to the diaphragm, an operating member rotatably carried by the frame, an element threaded to said member, means for holding the element against rotation with the member, said element engaging with and operating said lever against said spring device, whereby rotation of the member will cause an operation of said lever and through it an adjustment of the unit relatively to the diaphragm.
6. In a telephone receiver, a frame, a diaphragm carried by said frame, an electromagnetic unit mounted in said frame for movement toward and from the diaphragm and adapted to actuate the said diaphragm magnetically, a stud carried by the unit, a spring device constantly urging the unit in one direction relatively to the diaphragm, a lever articulately connected to said stud and having a fulcrum on the frame enabling operation of the unit in an opposite direction relatively to the diaphragm, an operating member rotatably carried by the frame, an element threaded to said member, means for holding the element against rotation with the member, said element engaging with and operating said lever against said spring device, whereby rotation of the member will cause an operation of said lever and through it an adjustment of the unit relatively to the diaphragm.
7. In a telephone receiver, a base, a diaphragm carried by the base in a position to set up sound waves when vibrated, an electromagnetic unit mounted in the base for movement toward and from the diaphragm and adapted to magnetically actuate the diaphragm, an operating member rotatably carried by the base and having a portion accessible from the outside of the base for manual operation, an element having a threaded connection with said operating member, means for holding the element against rotation with the member, and a lever fulcrumed at one end on said base and connected at an intermediate point to said unit to move it relatively to the diaphragm, said lever being operated at the other end by said element.
8. In a telephone receiver, a base, a diaphragm carried by the base in a position to set up sound waves when vibrated, an electromagnetic unit mounted in the base for movement toward and from the diaphragm and adapted to magnetically actuate the diaphragm, an operating member rotatably carried by the base and having a portion accessible from the outside of the base for manual operation, an element having a threaded connection with said operating member, means for holding the element against rotation with the member, a lever fulcrumed at one end on said base and connected at an intermediate point to said unit to move it relatively to the diaphragm, said lever being operated at the other end by said element in one direction, and a spring device for operating said unit in a direction to maintain the lever against the said element.
9. In a telephone receiver, a frame, a diaphragm carried by the frame, an electromagnetic diaphragm actuating unit carried by the frame and operable to vary its influence upon the diaphragm, an operating member rotatably carried by said frame and held against movement axially, an element threaded to said member and having a serrated peripheral portion, a pawl adapted to engage in any of the serrations and hold

said element against rotation with the operating member whereby the element will move axially of the member when the latter is rotated, and means controlled by said element for operating said unit to vary its influence upon the diaphragm.

10. In a telephone receiver, a pair of relatively movable parts, a diaphragm carried by one of the parts, an electromagnetic diaphragm actuating device carried by the other of said parts whereby when relative movement between the parts occurs the device and diaphragm will be given relative movements, an operating member rotatably carried by one of the parts and held against movement axially thereon, an element threaded to said member, means for holding said element against rotation with said member whereby when the latter is rotated 20 the element will be given movement axially of the member, and a lever magnetically independent of the electromagnetic device, but articulately connected therewith and controlled by said element for effecting relative movement between the said parts to 25

vary the influence of the device upon the diaphragm.

11. The receiver substantially as set forth in claim 10 in which the holding means for said element permits initial adjustment 30 of the element relatively to said member.

12. In a telephone receiver, a diaphragm, an electromagnetic device supported in position to actuate said diaphragm, an operating member mounted for rotation and held 35 against movement axially and having a portion adapted to be actuated manually, an element having a threaded connection with said member, means for holding said element against rotation with said member, 40 a lever magnetically independent of the electromagnetic device but articulately connected therewith and operated by said element for varying the influence of said device upon said diaphragm. 45

In witness whereof, we hereunto subscribe our signatures.

HENRY KOCH.

FRIEDRICH H. N. WOHLERS.
